GOLF BALL PACKAGE

Stanley J. Panek, Buffalo, N.Y., assignor to Dunlop Tire and Rubber Corporation, Buffalo, N.Y., a corporation of New York

Filed July 13, 1964, Ser. No. 80,836

Term of patent 14 years

(Cl. D58—2)

FIG. 1 is a front elevation of the golf ball package showing my design;

FIG. 2 is a side elevation thereof;

FIG. 3 is a rear elevation thereof;

FIG. 4 is a top plan view thereof; and

FIG. 5 is a bottom plan view thereof.

I claim:

The ornamental design for a golf ball package, as shown.
